SEATING ARRANGEMENT

William A. Brown, Philadelphia, Pa.

Application May 7, 1935, Serial No. 20,250

5 Claims. (Cl. 296—64)

My invention relates to a novel superimposed seating arrangement which can be employed in conjunction with any type of a vehicle used for transporting passengers such as, for example, 5 buses, trolley cars, trains, trams, boats, airplanes and dirigibles irrespective of whether the vehicle travels on land, water or in the air.

The prime object of this invention is to provide a commercially practical construction 10 wherein thoroughly comfortable individual seats are used for all forms of passenger transportation, without increasing the overall dimensions of standard bodies and more specifically without decreasing the passenger carrying capacity of 15 the vehicle.

Another object of this invention is to provide a superimposed seating arrangement in which the passenger's vision of surrounding objects, exterior to the vehicle body, closely approximates 20 and in many instances is superior to that of standard body construction.

Another object of this invention is to provide obliquely positioned upper and lower divisions of a superimposed seating arrangement to eliminate the disagreeable effects of a blank wall in 25 close proximity to the line of vision.

A further object of this invention is to provide obliquely positioned upper and lower divisions of a superimposed single seating arrangement 30 in order that each passenger may have adequate leg room without materially changing the overall length of the entire vehicle body, or the aisle space between rows of seats.

Another object of this invention is to provide 35 sufficient aisle space between rows of seats to expedite loading and unloading as well as ample standing room, if required.

In superimposed seating arrangements heretofore devised, it has been customary to provide 40 double seats at each side of a center aisle, the result of which is that the persons seated nearest the aisle do not have the same vision as those seated at the windows, and furthermore, where the seats are transversely disposed, so that they 45 extend straight across the vehicle, all that the occupants, adjacent to the aisles, can see when looking forward is a blank wall formed by the partitions.

It is therefore a further and primary object of 50 my invention to devise a novel seating arrangement wherein individual rotatable seats are provided for the passengers, which may be disposed at an angle to the length of the vehicle so that each passenger will have a clear forward and 55 side view through the windows. The arrange-

ment is preferably such that single individual seats are provided adjacent to the windows, in combination with a central longitudinal row of individual seats with aisles between the central row of seats and the side seats.

A further object of the invention is to provide 5 a novel seating arrangement of superimposed seats wherein either the upper or lower central row of seats is accessible from one aisle and the other row of central seats is accessible from the 10 other aisle.

With the above and other objects in view, as will hereinafter more clearly appear, my invention comprehends a novel seating arrangement. It further comprehends a novel superimposed, 15 individual seating arrangement which will provide proper ventilation, leg room, aisle space, and vision for each passenger.

Other novel features of construction and advantage will hereinafter more clearly appear in 20 the detailed description and the appended claims.

Figure 1 is a longitudinal section of a seating arrangement embodying my invention.

Figure 2 is a sectional view of the seating arrangement seen in Figure 1 the section being 25 taken substantially on line 2—2 of Figure 1.

Figure 3 is a transverse section, taken substantially on line 3—3 of Figure 1.

Figure 4 is a side elevation of a portion of a 30 seating arrangement embodying my invention.

Figure 5 is a schematic view of a permanent seating arrangement embodying my invention.

Similar numerals of reference indicate corresponding parts.

Referring to the drawings:

I designates a motor vehicle, illustrated as a bus construction, which is adapted to be driven by any type of motive power, and as these features do not form per se any part of my invention, I have deemed it unnecessary to illustrate and describe such mechanism and to only illustrate the wheels 2 which may have any desired type of tread, such as, for example, pneumatic or solid tires.

The body 3 of the vehicle is carried on girders 4, or their equivalent, which support the deck 5 and in the case of a bus it is provided at its forward end with a conventional loading platform entrance to which and exit from which 50 would be controlled in the conventional manner, by suitable doors controllable by the driver of the vehicle.

In Figures 1 to 4 inclusive I have illustrated the 55 preferred embodiment of my invention, wherein

the seating arrangement is such that individual side seats 6 and 7, a central row of individual seats 8 and two aisles 9 and 10, are provided. In this manner each passenger is provided with his own individual seat.

The compartments for the individual side seats 6 incline inwardly and rearwardly towards the aisle 10, while the compartments for the individual side seats 7 incline inwardly and rearwardly toward the aisle 9. The compartments for the individual central row of seats 8 have the same inclination as the compartments for the individual side seats 7 at the right hand side of the bus, so that the right hand row of seats and the central row of seats will have a clear vision through the right hand windows 11, and, of course, the occupants of the left hand row of seats 6 will have a clear vision through the windows 12. In many cases in practice the occupants 20 of all three rows of seats will have an unobstructed view through both sets of windows 11 and 12.

The seat compartments at the sides are formed by inclined partitions 13 which, in proximity 25 to the aisle, extend at right angles as shown at 14.

The central partitions 15 are of the same formation as the others and extend inwardly and rearwardly from the aisle 9, in an oblique direction 30 and then in a substantially straight line to the aisle 10.

The lower seats 6 and 7 are rotatably mounted on the support 16. The partitions 13 at the upper end terminate in a forward extension 17 35 on which the upper seats are rotatably mounted, and these seats, as will be apparent in the art, are out of alignment with the lower seats.

The top member 17 then extends downwardly as at 18 and forwardly as at 19 being connected 40 with the partition 13 in advance of it and forming a leg pocket 20 for the occupant of the upper seat. Access to the leg pocket is provided by the steps 21 which open into their respective aisle 9 or 10, at preferably substantially right 45 angles. The adjustable cover 28 may be moved up or down by the passenger to open or close the space necessary to allow easy access to the steps 21.

The forwardly extending portion 17 of the partitions are reinforced by means of the bars or rods 22 connected thereto and to the roof of the passenger seating compartment in any desired or conventional manner. These bars or rods 22 not only form reinforcing members, but also 50 form grasping handles for the passenger passing to and from an upper seat at the right or left hand portion of the vehicle. If a passenger is moving up the steps 21 to pass to an upper seat 6 he grasps a bar or rod 22 with his right hand 55 and the arm of the seat, which he is to occupy, with his left hand so that he is fully protected in passing to an upper seat and is not liable to fall or stumble. It will be apparent, from the 60 illustrations shown, that the steps 21 are within the seating compartment so that the aisles 9 and 10 are not obstructed.

The central row of seats 8, as before explained, are preferably turned toward the right so that the occupants will naturally look through the 65 windows 11. Steps 23 for the central aisle are similar to the steps 21 in construction and are contained within central lower seating compartment. The adjustable cover plate 29 is similar to the adjustable cover plate 28, already described.

Entrance to and exit from the lower central seats 8 is through the aisle 9 while entrance to and exit from the upper central seats 8 is through the aisle 10. Reinforcing bars or rods 24 extend from the roof to the central partitions 15, 5 which, it will be understood, extend forwardly at the upper ends to support the upper seats and then downwardly and forwardly to form leg pockets for the occupants of the upper seats and these leg pockets are provided with aprons 25 10 on the side next to the aisle 9.

I also provide the bars or rods 26 extending from the roof to the forwardly extending portion of the central partitions 15. The supports 16 are raised above the floor line 27 for the lower 15 seats.

In the embodiment shown in Figure 4, I show the upper and lower seats as being in fixed position, instead of being rotatably mounted, it being apparent that in accordance with this invention, either the lower seats, or the upper seats, or both the upper and lower seats may be fixed or may be rotatable. One row of seats may be fixed and the other row rotatable, or any selected seats may be fixed or rotatable as desired and still be within the spirit and scope of the invention.

A passenger entering the vehicle and intending to occupy the lower seat 6 enters the aisle 10 and steps down into the compartment for 30 his seat, and, in a similar manner, a passenger who desires to occupy a lower central seat enters the aisle 9 and steps down into the compartment for his seat. It will be apparent that beneath these lower seats there is a storage space 35 for the baggage of the passenger.

If the passenger desires to occupy an upper left hand seat he enters the left aisle 10 and walks up the steps 21 into the compartment containing the upper seat. If the passenger desires to occupy a seat in the upper central row of seats he enters the aisle 10 and steps up into the compartment for an upper seat. If the passenger desires to occupy an upper right hand seat he enters the aisle 9 and steps up into the compartment in which his seat is located. It will thus be apparent that the entrance and exit of the passengers will be controlled and evenly divided, with one half using aisle 9 and the other half using aisle 10.

It will be apparent that an individual seat is provided for each occupant of the passenger seating compartment. The occupants of the lower seats in the right and left hand rows, each has his own individual window and the same is true of the upper seats, in such rows. The occupants of the superimposed central rows of seats preferably look towards the right. All of the upper seats have in proximity to them grasping bars whereby the passenger can safely pass to and from the seat which he has selected.

While the seats are preferably all rotatably mounted, they can be selectively fixed and the advantages of my seating arrangement can be attained. While each passenger preferably turns his seat at an angle, he may, at his option, face forwardly or be positioned at any desired angle within the range for which the construction is built.

It will be apparent from the foregoing disclosure of this invention that I provide the same luxurious seating comfort to be found in a conventional parlor car seating arrangement as used by railroads, without increasing the overall dimension of standard bodies and more specifically

without decreasing the passenger carrying capacity of the vehicle.

It will also be apparent that each passenger will have a clear unobstructed view of the scenery on both sides of the vehicle. There are no blank walls in close proximity to the line of vision.

It will further be apparent that in my present oblique seating arrangement I provide a substantial increase of leg room for the passengers. If we assume that the distance between the partitions is thirty-six inches and that the front to back depth of a seat is about nineteen inches then instead of obtaining a leg room of only seventeen inches, a leg room is obtained which is substantially from twenty-six inches to twenty-eight inches. This, of course, is brought about because the seating compartments are angularly disposed relative to the longitudinal axis of the vehicle and the seats are preferably rotatable to make this excess of leg room instantly available, or they may be permanently fixed in an oblique position to take advantage of this extra leg room.

If we assume that the width of the seating compartment is ninety inches the arrangement may be such that each aisle will be eighteen inches in width as well as each seating compartment. This provides thirty-six inches of aisle space as compared to the conventional aisle space of about twenty inches where regular double seating is used. This additional aisle space not only enables the passengers to more readily pass to and from the seats but it also materially increases the standing space if the aisles are used, in emergency, to take care of overcrowding.

A standard single deck bus of thirty-three feet overall length using a conventional seating arrangement has a maximum capacity of thirty-two passengers and to obtain individual seating comparable to what is provided for in this invention would require an overall length in excess of forty-five feet which is prohibitive under present traffic conditions.

In my present construction I am also able to allow a clearance of thirty-nine inches between the top of the seat proper and the ceiling directly over each passenger's head, within a maximum height of the body shown from floor to ceiling, of only ninety-seven inches.

While I have shown a seating arrangement employing two aisles with a central row of seats between said aisles it is to be understood that said central row of seats may be dispensed with and a single aisle employed between the two outer rows of seats.

Having thus described my invention what I claim as new and desire to secure by Letters Patent, is:—

1. An enclosed passenger seating arrangement for vehicles with side windows, upper and lower compartments in proximity to said windows at one side of the vehicle, said lower compartments having upright partitions extending obliquely

from the entrances to said compartments to the sides of the vehicle, seats in said compartments, and a row of lower seats removed from a side wall of the vehicle.

2. An enclosed passenger seating arrangement for vehicles with side windows, upper and lower compartments in proximity to said side windows at one side of the vehicle, the upper of said compartments having leg pockets extending obliquely from the entrances to said compartments to the side of the vehicle, said lower compartments having upright partitions extending obliquely from the entrances to said compartments to the sides of the vehicle, seats in said compartments, and a row of lower seats removed from a side wall of the vehicle.

3. An enclosed passenger seating arrangement for vehicles having side windows, and spaced longitudinally extending aisles, upper and lower compartments in proximity to said aisles, and certain of which are removed from a side wall of the vehicle, the upper of said compartments between an aisle and a vehicle side wall having leg pockets extending obliquely from the entrances to said compartments to the sides of the vehicle, the corresponding lower compartments having upright partitions extending obliquely from the entrances to said compartments to the sides of the vehicle, and seats in said compartments, said obliquely positioned leg pockets and partitions providing for adequate visibility through said windows for the occupants of the lower seats removed from a vehicle side.

4. An enclosed passenger seating arrangement for vehicles having side windows, upper and lower compartments in proximity to side windows at one side of the vehicle, said lower compartments having upright partitions extending obliquely from the entrances to said compartments to the side of the vehicle, seats for said compartments, a row of upper and lower compartments removed from said one side of the vehicle, and seats for said last named compartments, the arrangement of said partitions providing for adequate visibility through said side windows for occupants of the lower seats.

5. An enclosed passenger seating arrangement for vehicles having side windows, upper and lower compartments in proximity to said side windows, the upper of said compartments having leg pockets extending obliquely from the entrances to said compartments to the sides of the vehicle, said lower compartments having upright partitions extending obliquely from the entrances to said compartments to the sides of the vehicle, a plurality of spaced rows of upper and lower compartments removed from the sides of the vehicle, and seats for said last named compartments, the arrangement of said leg pockets and partitions providing adequate visibility through said side windows for all the occupants of the seats.

WILLIAM A. BROWN.
